[57] ABSTRACT

In a tool having opposed jaws and lever-actuated mechanism for drawing the jaws together to fit against threaded parts of various sizes, the lever-actuated mechanism comprises a pivotally mounted lever and force transmitting means movable over an arcuate path in substantially parallel relation to a sliding member formed with a series of ratchet teeth.

TOOL FOR USE AS JAR AND BOTTLE OPENER

This is a continuation of application Ser. No. 795,284, filed Jan. 30, 1969, now abandoned.

BACKGROUND OF THE INVENTION

This invention pertains generally to a tool for household use and more particularly to improved tools of the type having opposed jaws and lever-actuated mechanism for drawing the jaws together to fit against threaded parts of various sizes. Such tools are particularly adapted for use in opening jars and bottles having screw-type lids but also may be used in diverse other applications.

In such a tool, it is desirable that the lever-actuated mechanism be capable of being operated with one hand, easily and untiringly, in such a manner as to draw the jaws together from widely spaced positions to fit against threaded parts of various sizes, thereby leaving the other hand of the operator free to grasp the articles on which the threaded parts are to be loosened or tightened. The household tools known to the prior art have proved to be not entirely satisfactory in this regard.

An early example of the prior art in a household tool for use in opening jars and bottles having screw-type lids is disclosed in a patent to Franz K. Krag, U.S. Pat. No. 2,000,962. The tool is characterized by an elongated generally U-shaped handle having a series of ratchet teeth along the inner edge of one leg. A first jaw is fixed to the handle. A second jaw forms part of structure slidably mounted to the handle. A lever is pivotally mounted to the same structure. A pawl is pivotally mounted to the handle. After the jaws have been pushed together manually to fit against a screw-type lid on a jar or bottle, the lever may be actuated to move the pawl into engagement with the ratchet teeth in substantially perpendicular relation to the series of ratchet teeth. Further actuation of the lever transmits leverage to the jaws through the pawl.

Improvements to the tool described in the preceding paragraph are disclosed in a later patent to Franz K. Krag, U.S. Pat. No. 2,634,638. In the improved tool, the lever is spring-biased outwardly, and the pawl is spring-biased toward the ratchet teeth. A lug on the lever engages the pawl and draws the pawl out of engagement with the ratchet teeth upon release of the lever. The pawl is moved into engagement with the ratchet teeth in substantially perpendicular relation to the series of ratchet teeth, whereupon the mechanical advantage of the tool is high but there is substantial friction between the handle and the structure of which the second jaw forms part. Furthermore, the configurations of the handle and the lever make the tool somewhat inconvenient to use, particularly in opening a wide mouthed jar or bottle.

Another example of the prior art in a household tool for use in opening jars and bottles having screw-type lids is disclosed in a patent to Philip F. Marsella et al., U.S. Pat. No. 2,236,342. The tool has a lever-actuated mechanism which is used to advance the elongated shank of a slider relative to an elongated handle in incremental movements in order to draw together an integral jaw on the slider and an integral jaw on the handle. The shank of the slider is formed with a series of ratchet teeth. The lever-actuated mechanism comprises an elongated generally straight lever, which is pivotally mounted to the handle, and a pawl, which is pivotally mounted to the lever. The lever is spring-

biased outwardly of the handle, and the pawl is spring-biased toward the ratchet teeth, whereupon repeated actuation of the lever advances the shank of the slider relative to the handle. The pawl is moved into engagement with the ratchet teeth in substantially perpendicular relation to the ratchet teeth, whereupon there is substantial friction between the slider and the handle. Furthermore, the operation of the tool is not entirely satisfactory in that there is no readily apparent way for the pawl to be held out of engagement with the ratchet teeth in order to permit the shank of the slider to be withdrawn from the handle.

There remains a need for an improved tool of the type having opposed jaws and lever-actuated mechanism for drawing the jaws together which is capable of being operated with one hand, easily and untiringly, in such a manner as to draw the jaws together from widely spaced positions to fit against threaded parts of various sizes.

SUMMARY OF THE INVENTION:

Accordingly, it is one object of this invention to provide an improved tool of the aforementioned type which is designed to be operated with one hand, easily and untiringly, in such a manner as to draw the jaws together from widely spaced positions to fit against threaded parts of various sizes.

It is another object of this invention to provide a tool, as described, which leaves the other hand of the user free to grasp the article on which the threaded parts are to be loosened or tightened.

Similarly, it is another object of this invention to provide a tool, as described, which may be used in cramped quarters.

It is another object of this invention to provide a tool, as described, in which there is no need to push the jaws together manually.

It is yet another object of this invention to provide a tool, as described, which is particularly adapted for use in opening jars and bottles having screw type lids.

The preceding objects are attained in a tool comprising a handle having a jaw portion, a sliding member having an elongated shank portion slidably mounted to the handle and a jaw portion, and lever-actuated mechanism for effecting longitudinal sliding movement of the sliding member in one direction with respect to the handle. The jaw portion of the sliding member and the jaw portion of the handle are oriented so as to be drawn together upon longitudinal sliding movement of the sliding member in the aforesaid one direction with respect to the handle and to be drawn apart upon longitudinal sliding movement of the sliding member in the opposite direction with respect to the handle.

More particularly, the lever-actuated mechanism comprises a lever pivotally mounted to the handle in combination with force transmitting means for transmitting force from the lever to the sliding member by engagement with a series of ratchet teeth formed on the shank portion of the sliding member. The force transmitting means is connected to the lever so as to effect incremental longitudinal sliding movement of the sliding member in the aforesaid one direction with respect to the handle upon pivotal actuation of the lever and so as to be disassociated from the sliding member upon release of the lever.

In accordance with the principles of this invention, the force transmitting means is connected to the lever

so as to be movable into and out of engagement with the ratchet teeth over an arcuate path in substantially parallel relation to the series of ratchet teeth. As a result, force applied to the lever is transmitted to the shank portion of the sliding member in the direction of intended movement of the sliding member, whereupon there is minimal friction between the shank portion of the sliding member and the handle. The lever may be repeatedly actuated with minimal effort to advance the sliding member with respect to the handle in incremental movements.

Force transmitting means of various types may be employed satisfactorily. Thus, for example, the force transmitting means may comprise a pawl pivotally mounted to the lever and biased toward the ratchet teeth. Alternatively, the force transmitting means may comprise a tongue in cantilevered relation to the lever. In the latter instance, the tool would require only two moving parts, exclusive of the handle and biasing means.

Other objects of this invention are to provide a tool which is free of sharp corners or edges and is convenient to use by virtue of an asymmetrically shaped handle designed for comfort in handling, to provide a tool of simplified construction with a minimum number of moving parts, to offer the lowest possible cost to consumers by virtue of simplified construction and a minimum number of parts, to provide a tool which may be hung on a conventional kitchen rack, and to provide a tool of highly functional design incorporating materials commonly used in household tools.

These and other objects, features, and advantages of this invention will be evident from the description to follow, with the aid of the attached drawing, of a preferred embodiment of this invention having several alternative arrangements of parts.

BRIEF DESCRIPTION OF THE DRAWINGS

In the drawings:

FIG. 1 is a longitudinal sectional view of a tool embodying the principles of this invention, one arrangement of parts being shown;

FIG. 2 is a sectional view taken substantially along line 2—2 of FIG. 1 in the direction of the arrows, subject matter normally appearing in the background being omitted for clarity;

FIG. 3 is a sectional view taken substantially along line 3—3 of FIG. 1 in the direction of the arrows, subject matter normally appearing in the background being omitted for clarity;

FIGS. 4—6 are fragmentary views, similar to FIG. 1, showing an alternative arrangement of parts; and

FIG. 7 is a detail view taken substantially along line 7—7 of FIG. 6 in the direction of the arrows, showing the relationship of some of the parts.

DESCRIPTION OF THE PREFERRED EMBODIMENT

In the drawings, in which corresponding parts are indicated by like reference numbers, there is shown a tool 10 embodying the principles of this invention. The tool 10 comprises a handle 12 which is free of sharp corners or edges and is asymmetrically shaped for comfort in handling. The handle 12 has an elongated body portion 14 and a widened jaw portion 16 and is generally hollow, as shown. The tool 10 further comprises a

sliding member 18 having an elongated shank portion 20 and a jaw portion 22.

For convenience in assembly, the handle 12 is formed in two separate pieces or members, 26 and 28 respectively, which may be molded of high-impact plastic or metal, the former being preferred. A first rivet 30 and a second rivet 32 are used to fasten together the handle members 26 and 28 at the jaw portion 16 of the handle 12. A third rivet 34 is used to fasten together the handle members 26 and 28 at the body portion 14 of the handle 12. The rivet 30 passes through an annular spacer 36, which projects inwardly from the inside surface 38 of the handle member 26, and through an annular spacer 40, which projects inwardly from the inside surface 42 of the handle member 28. The annular spacers 36 and 40 are tightly drawn together by the rivet 30 and, in a manner to be described hereinafter, provide pivotal support for the lever-actuated mechanism 24. The rivets 32 and 34 pass through similar annular spacers (not numbered) projecting inwardly from the inside surfaces 38 and 42 of the respective handle members 26 and 28, as shown.

Preferably, the sliding member 18 is fabricated from a sheet metal strip. The shank portion of the sliding member 18 is slidably mounted to the handle 12, for longitudinal sliding movement of the sliding member 18 with respect to the handle 12, and is guided within a cavity 48 in the handle 12. The jaw portion 22 of the sliding member 18 extends outwardly from the jaw portion 16 of the handle 12 through a widened slot 50 in the jaw portion 16 of the handle 12. The inner end 60 of the shank portion 20 of the sliding member 18 is bent at a right angle toward the handle member 26 and is guided between a longitudinal ridge 62 on the inside surface 38 of the handle member 26 and a longitudinal ridge 64, suitably spaced therefrom, on the inside surface 42 of the handle member 28. The bent end 60 engages a generally transverse ridge 66 on the inside surface 38 of the handle member 26, in order to limit longitudinal sliding movement of the sliding member 18 outwardly with respect to the handle 12 and thus prevent the sliding member 18 from becoming accidentally dissociated from the handle 12.

The jaw portion 22 of the sliding member 18 and the jaw portion 66 of the handle 12 are oriented so as to be drawn together upon longitudinal sliding movement of the sliding member 18 inwardly with respect to the handle 12 and so as to be drawn apart upon longitudinal sliding movement of the sliding member 18 outwardly with respect to the handle.

An integral jaw 74, preferably serrated as shown, is provided on the jaw portion 16 of the handle 12. As shown, the jaw 74 is molded in one piece with the handle member 26, but, alternatively, the jaw 74 may be in the form of a separate piece fixedly attached to the jaw portion 16 of the handle 12. An integral jaw 76, preferably formed with an enlarged V-groove 78, is provided on the jaw portion 22 of the sliding member 18. As shown, the outer end of the sliding member 18 is bent over and back to form the jaw 76, but, alternatively the jaw 76 may be in the form of a separate piece fixedly attached to the jaw portion 22 of the sliding member 18. The jaws 74 and 76 are adapted to be drawn tightly against opposite portions of a threaded article, such as the exemplary screw-type lid or closure for a jar or bottle indicated in phantom outline at 80

(FIGS. 1 and 2), by means of the lever-actuated mechanism 24 next to be described.

The lever-actuated mechanism 24, which may be actuated to effect longitudinal sliding movement of the sliding member 18 inwardly with respect to the handle 12, comprises a lever 90 pivotally mounted to the handle 12 in combination with force transmitting means 92 for transmitting force from the lever 90 to the sliding member 18.

The lever 90 which preferably is fabricated from a sheet metal blank, is generally L-shaped and has a lever-arm portion 94 and an extended portion 96. The lever-arm portion 94 moves within a cavity 98 in the handle 12 and is pivotally mounted to the handle 12 by means of the aforementioned annular spacers 36 and 40 around the rivet 30. As shown, the lever arm portion 94 of the lever 90 has a pair of spaced parallel legs, 100 and 102 respectively, which are disposed on opposite sides of the shank portion 20 of the sliding member 18, and a connecting web 104. The annular spacers 36 and 40 extend through suitably circular openings (not numbered) in the respective legs 100 and 102 and define a pivot axis about which the lever 90 is pivotable.

The extended portion 96 of the lever 90 extends outwardly from the jaw portion 16 of the handle 12, through a widened slot 110 in the jaw portion 16 of the handle 12, and is adapted to be drawn toward and away from the body portion 14 of the handle 12 for pivotal movement of the lever 90 between a first (or opened) position, wherein the extended portion 96 of the lever 90 and the body portion 14 of the handle 12 are spread apart, and a second (or closed) position, wherein the extended portion 96 of the lever 90 and the body portion 14 of the handle 12 are closed together. In FIGS. 1, 4, and 5, the lever 90 is shown in the first (or opened) position in full lines and in the second (or closed) position in dashed lines. The lever 90 is biased to the opened position means of a wire spring 112 which is coiled around the annular spacers 36 and 40, between the legs 100 and 102 of the lever-arm portion 94 of the lever 90, one end 114 of the spring 112 being pressed against the inclined ridge 66 on the handle member 28 and the other end 116 of the spring 112 being bent back and hooked onto the leg 100.

Preferably, the handle 12 provides an integral stop for the lever 90 in the opened position and an integral stop for the lever 90 in the closed position. As shown, movement of the lever 90 between the opened and closed positions is limited by engagement of the lever 90 with the margins (not numbered) of the opening 110.

In the embodiments of FIGS. 1-5, the shank portion 20 of the sliding member 18 is provided with a series of ratchet teeth 120 along one narrow edge 122. In the embodiment of FIGS. 6 and 7, the shank portion 20 of the sliding member 18 is provided with a series of ratchet teeth 120', which are laterally engageable from one wide surface 124, adjacent to the narrow edge 122. As shown, the ratchet teeth 120 (or 120') are oriented so as to prevent longitudinal movement of the sliding member 18 outwardly with respect to the handle 12 during engagement by the force transmitting means 92.

In each of the illustrated embodiments, the force transmitting means 92 is connected to the lever-arm portion 94 of the lever 90 in such a manner as to effect incremental longitudinal sliding movement of the slid-

ing member 18 inwardly with respect to the handle 12 upon pivotal movement of the lever 90 from the first (or opened) position to the second (or closed) position. Furthermore, in accordance with the principles of this invention, the pivot axis of the lever 90, which is defined by the annular spacers 36 and 40, and the point at which the force transmitting means 92 is connected to the lever-arm portion 94 of the lever 90, are widely spaced apart from the respective opposite narrow edges of the shank portion 20 of the sliding member 18. This relationship should be evident from the drawing. As a result, the force transmitting means 92 is movable over an arcuate path in substantially parallel relation to the series of ratchet teeth 120 (or 120'), thereby to be disengaged from the ratchet teeth 120 (or 120') when the lever 90 is in the first (or opened) position to the second (or closed) position. Such movement of the force transmitting means 92 permits force to be transmitted from the lever 90 to the sliding member 18 in a direction substantially parallel to the direction of intended movement of the sliding member 18. As a result, there is minimal friction between the shank portion 20 of the sliding member 18 and the body portion 14 of the handle 12, and the lever 90 may be repeatedly actuated, with minimal effort, in order to advance the sliding member 18 with respect to the handle 12 in incremental movements.

In the embodiment of FIGS. 1-3, the force-transmitting means 92 comprises a generally U-shaped pawl 130 pivotally mounted to the lever 90, between the legs 100 and 102 of the lever-arm portion 94, on a pin 132 which is adjacent to the connecting web 104. The pawl 130 is movable with the lever 90, over an arcuate path in substantially parallel relation to the series of ratchet teeth 120, and is adapted to clear the ratchet teeth 120 when the lever 90 is in the first (or opened) position and to be moved into engagement with the ratchet teeth 120 upon pivotal movement of the lever 90 from the first (or opened) position to the second (or closed) position. The pawl 130 is biased toward the ratchet teeth 120 by means of a wire spring 134 which is coiled around the pin 132. One end 136 of the spring 134 is pressed against the connecting web 104 of the lever-arm portion 94 of the lever 90. The other end 138 of the spring 134 is pressed against the pawl 130. The connecting web 104 of the lever-arm portion 94 of the lever 90 is engaged by a portion 140 of the pawl 130 and thereby limits pivotal movement of the pawl 130 toward the ratchet teeth 120, such that the pawl 130 is adapted to clear the ratchet teeth 120 when the lever 90 is in the opened position, and such that the pawl 130 is forced out of engagement with the ratchet teeth 120 upon release of the lever 90.

In the embodiment of FIG. 4, the force-transmitting means 92 comprises a generally U-shaped pawl 142 pivotally mounted to the lever 90, between the legs 100 and 102 of the lever-arm portion 94, on a pin 144 which is adjacent to the connecting base 104. The pawl 142 is movable with the lever 90, over an arcuate path in substantially parallel relation to the series of ratchet teeth 120, and is adapted to clear the ratchet teeth 120 when the lever 90 is in the first (or opened) position and to be moved into engagement with the ratchet teeth 120 upon pivotal movement of the lever 90 from the first (or opened) position to the second (or closed) position. The pawl 142 is biased toward the ratchet teeth 120 by means of a wire spring 146 which is coiled

around the pin 144. One end 148 of the spring 146 is pressed against the connecting web 104 of the lever-arm portion 94 of the lever 90. The other end 140 of the spring 146 is pressed against the pawl 142. Transverse ridges 152 on the inside surfaces 38 and 42 of the respective handle members 26 and 28 are engaged by portions 154 of the pawl 142 upon pivotal movement of the lever 90 from the closed position to the opened position, such that the pawl 142 is adapted to clear the ratchet teeth 120 when the lever 90 is in the opened position, and such that the pawl 142 is forced out of engagement with the ratchet teeth 120 upon release of the lever 90.

In the embodiment of FIG. 5, the force transmitting means 92 comprises a tongue 156, in cantilevered relation to the lever 90, movable with the lever 90 over an arcuate path in substantially parallel relation to the series of ratchet teeth 120. The tongue 156 is connected to the lever-arm portion 94 of the lever 90 adjacent to the connecting base 104, as shown, and is adapted to clear the ratchet teeth 120 when the lever 90 is in the first (or opened) position to the second (or closed) position. Thus, full movement of the lever 90 from the first (or opened) position to the second (or closed) position effects incremental movement of the sliding member 18 inwardly with respect to the body 12. The ratchet teeth 120 are shallow, as shown, in order to permit the tongue 156 to be disengaged substantially without movement of the sliding member 18 in the opposite direction with respect to the handle 12.

The tongue 156 may be formed in one piece with the lever 90. As shown in FIG. 5, an integral portion of the lever 90 at the connecting web 104 of the lever-arm portion 94 is bent under, at an acute angle, in order to form the tongue 156. Thus, in the embodiment of FIG. 5, the tool 10 requires only two moving parts, exclusive of the handle 12 and the wire spring 112, namely, the sliding member 18 and the lever 90. Alternatively, a separate member (not shown) may be rigidly attached to the lever 90 so as to form the tongue 156.

The embodiment of FIGS. 6 and 7 is similar to the embodiment of FIG. 5 in that the force transmitting means 92 comprises a tongue 160 in cantilevered relation to the lever 90. However, as shown, the tongue 160 is in the form of a separate member which is rigidly attached to the leg 100 of the lever-arm portion 94 of the lever 90 by means of a pair of spaced rivets 162 which are adjacent to the connecting web 104. Alternatively, an integral portion of the lever 90 may be bent so as to form the tongue 160. The tongue 160 is movable with the lever 90, over an arcuate path in substantially parallel relation to the series of ratchet teeth 120', and is adapted to clear the ratchet teeth 120' when the lever 90 is in the opened position and to be moved into engagement with the ratchet teeth 120' upon pivotal movement of the lever 90 from the opened position to the closed position. Thus, full movement of the lever 90 from the first (or opened) position to the second (or closed) position effects incremental movement of the sliding member 18 inwardly with respect to the handle 12. The ratchet teeth 120' are shallow, as shown, in order to permit the tongue 160 to be disengaged without substantial movement of the sliding member 18 in the opposite direction with respect to the handle 12.

In each of the illustrated embodiments, because the force transmitting means 92 is movable in substantially parallel relation to the series of ratchet teeth 120 (or

120'), there is little friction between the sliding member 18 and the handle 12. Thus, the lever 90 may be actuated with minimal effort to draw together the jaw portion 22 of the sliding member 18 and the jaw portion 16 of the handle 12, and repeated actuation of the lever 90 to effect advancement of the sliding member 18 in incremental movements is virtually effortless. Of consequence, the tool 10 may be operated with one hand, leaving the other hand of the operator free to hold the work object.

10 As an added feature, means may be provided for exerting a slight frictional drag on the shank portion 20 of the sliding member 18. A helical spring 170, which is piloted over an inwardly projecting post 172 on the inside surface 38 of the handle member 26, gently presses against the shank portion 20 of the sliding member 18. The spring 170 serves to prevent the sliding member 18 from slipping with respect to the handle 12 but has only minimal effect on the required longitudinal sliding movement of the sliding member 18 with respect to the handle 12.

15 Modifications and improvements within the scope of this invention may be suggested by the foregoing description to those skilled in the art. Accordingly, the scope of this invention should be determined from the following claims.

20 I claim:

1. A tool comprising, in combination, a handle having a jaw portion, a sliding member having an elongated shank portion formed with a series of ratchet teeth and slidably mounted to the handle for longitudinal sliding movement of said sliding member with respect to said handle and a jaw portion oriented so as to be drawn toward the jaw portion of said handle upon longitudinal sliding movement of said sliding member in one direction with respect to said handle and so as to be drawn apart from the jaw portion of said handle upon longitudinal sliding movement of said sliding member in the opposite direction with respect to said handle, a lever pivotally mounted to said handle for pivotal movement between a first position and a second position, means for biasing said lever to said first position, said biasing means positioning said lever in said first position except when said lever is drawn toward said second position, said handle engaging said lever to provide an integral stop for said lever in said first position and an integral stop for said lever in said second position, and force transmitting means for transmitting force from said lever to said sliding member to effect incremental longitudinal sliding movement of said sliding member in said one direction upon pivotal movement of said lever from said first position to said second position, said force transmitting means comprising a pawl pivotally mounted to said lever for pivotal movement toward and away from said ratchet teeth and movable with said lever over an arcuate path in substantially parallel relation to the series of ratchet teeth, said pawl being free of any contact with said handle over the range of pivotal movement of said lever, and means for biasing said pawl independently of said lever so as to move said pawl into engagement with said ratchet teeth upon pivotal movement of said lever from said first position to said second position, a portion of said lever being adapted to engage a portion of said pawl to limit pivotal movement of said pawl toward said ratchet teeth and carry said pawl out of engagement with said ratchet teeth upon pivotal movement of said lever from said second position to said first position, whereby said lever is returned to said first position and said pawl is disengaged from said ratchet teeth upon release of said lever from said second position.
